ADJUSTABLE TRANSMISSION LINE

Nicholas V. Fedotoff, Lynbrook, N. Y., assignor, by
mesne assignments, to Hazeline Research, Inc.,
Chicago, Ill., a corporation of Illinois

Application February 27, 1945, Serial No. 579,975

12 Claims. (Cl. 178—44)

1

This invention is directed to transmission lines of adjustable electrical length. While the invention is subject to a variety of applications, it is especially suited to short-circuited transmission lines and will be particularly described in that connection.

Short-circuited transmission lines of the type under consideration comprise a pair of conductors usually arranged in either spaced parallel or coaxial relationship to have uniformly distributed inductance and capacitance. The effective electrical length of such a line may be adjusted by means of a short-circuiting element bridged across and freely slideable along its conductors. Where the adjustment of the short-circuiting element is such that the electrical length of the line plus its terminating impedance is equal to one-quarter of its operating wave length, or an integral multiple thereof, the line exhibits impedance characteristics analogous to those of conventional resonant circuits and is said to be a resonant line. Since the frequency-response characteristic of a resonant line may be readily modified through adjustment of its short-circuiting or tuning element and in view of other well-recognized properties of line arrangements, resonant lines are widely used as frequency-selective or frequency-determining circuits of wave-signal translating apparatus designed for operation at ultra-high frequencies.

In one short-circuited line arrangement of the prior art, the position of the tuning element is adjustable through a mechanical link disposed along the line in the space between its conductors and affixed to the tuning element, the link and tuning element together constituting a tuning plunger axially movable along the line. While arrangements of this type have proved to be operative, they have certain inherent limitations which may be objectionable in particular installations. For example, as the tuning plunger is withdrawn from the line to increase its electrical length, the over-all physical length of the arrangement is increased progressively. Where space limitations are important, this feature may be undesirable.

In another line structure of the prior art in which the conductors have a coaxial or concentric relationship, the inner conductor is rotatably supported and is provided with a screw thread adapted to engage a threaded bushing of the tuning element. Additionally, the tuning element is slidably mounted on one or more guide rods positioned in the interconductor space which lock the tuning element against rotation. With this con-

2

struction, rotation of the inner conductor advances the tuning element along the line for tuning. This construction has the advantage that the physical dimensions of the structure do not vary with tuning. However, from a mechanical standpoint it is desirable that the inner conductor be made of steel but steel is a poor conductor at ultra-high frequencies. Furthermore, it is necessary to lubricate the threaded portion of the inner conductor whereas best operation of the line requires that its conductors be maintained clean. Additionally, the discontinuities in the skin of the inner conductor resulting from the screw thread may impair the conductive characteristics of the transmission line.

It is an object of the invention, therefore, to provide a transmission line of adjustable electrical length which avoids one or more of the above-mentioned limitations of prior art arrangements.

It is a further object of the invention to provide an improved transmission line of adjustable electrical length having reduced space requirements.

A transmission line of adjustable electrical length in accordance with the invention comprises a first conductor and a second conductor, the latter having an axially extending slot and a predetermined spaced relation to the first conductor. An adjustable member is movable in a

predetermined path in the space between the conductors for varying the electrical length of the transmission line including these conductors. The arrangement also comprises a driving member disposed within the second conductor for exerting a controllable driving force along the line.

The line also has means projecting through the slot of the second conductor into mechanical-coupling engagement with the adjustable member and the driving member for effecting a displacement of the adjustable member along its path by the driving member.

For a better understanding of the present invention, together with other and further objects thereof, reference is had to the following description taken in connection with the accompanying drawings, and its scope will be pointed out in the appended claims.

In the drawings, Fig. 1 is a cross-sectional view, partially broken away, of a transmission line constructed in accordance with the invention; Figs. 2 and 3 are additional sectional views taken as indicated by section lines 2—2 and 3—3, respectively, of Fig. 1; Fig. 4 is a schematic representation of a wave meter arrangement utilizing the transmission line of Figs. 1-3, inclusive; Fig. 5 is

a cross-sectional view of a further embodiment of the invention; Figs. 6, 7 and 8 are additional sectional views taken as indicated by section lines 6—6, 7—7 and 8—8, respectively, of Fig. 5; and Fig. 9 is a schematic circuit diagram of a power-bridge network utilizing the transmission line of Figs. 5-8, inclusive.

Referring now more particularly to Figs. 1, 2 and 3, the transmission line there represented is of the coaxial or concentric type. It comprises a hollow outer, or first, conductor 10 and a hollow inner, or second, conductor 11, each of which is circular in cross section. The second conductor is coaxially disposed within the first conductor so as to have a predetermined spaced relation with reference thereto. A pair of centrally apertured end plates 12 and 13 of conductive material are fitted to the opposite ends of conductor 10. A conductive bushing 14, inserted into the aperture of end plate 12 and nonrotatably supported thereby, is received by one end of conductor 11 to establish the desired coaxial alignment of the inner and outer conductors. The alternate end of conductor 11 is supported in a manner described hereinafter, to complete the desired coaxial alignment of these conductors. One or more machine screws 15, locking conductor 11 to bushing 14, hold the inner conductor against rotation. An axially extending or longitudinal slot 16 is milled into conductor 10 and similar but diametrically spaced slots 17 and 18 are cut into conductor 11. In assembling the line arrangement, its conductors are so oriented that slots 16, 17 and 18 are in vertical alignment.

The transmission-line structure includes an adjustable member movable in a predetermined path in the space between conductors 10 and 11 for varying the electrical length of the line constituted by, or including, these conductors. For the illustrated arrangement, this adjustable member short-circuits the inner and outer conductors to determine the electrical length of the line and is provided by a ring 20 having a series of resilient contact fingers 21 and 22 disposed about its inner and outer peripheries. Contact fingers 21 and 22 are suitably formed and proportioned to engage the inner and outer conductors of the line so that the short-circuiting member is supported by and freely movable along these conductors in the space therebetween.

A driving member is disposed within the second or inner conductor 11 of the line for exerting a controllable driving force therealong and for aiding in establishing the coaxial alignment of the inner and outer conductors. This driving member is provided by a rotatable shaft 24 a portion of which is threaded, as indicated at 25, to form a lead screw. One end of shaft 24 is rotatably supported in a bearing 26 secured to a centrally located recess in the end of bushing 14 which is adjacent this end of shaft 24. Preferably, bushing 26 is constructed of an oil-impregnated material to be self-lubricating. The opposite end of the shaft is rotatably supported in a bearing 27 retained in end plate 13 by means of retaining rings 28 and 29. This shaft also projects through a bushing construction 30 carried by the free end of conductor 11 and serves to maintain the coaxial alignment of conductors 10 and 11. The free end of shaft 24 extends beyond end plate 13 and supports a crank 31 through which the rotation of the lead screw may be controlled.

In order that the adjustable short-circuiting member 20, 21, 22 may be selectively displaced along the transmission line under the control of

lead screw 25, the line arrangement includes means projecting through the slots 17 and 18 of the inner conductor into mechanical-coupling engagement with both the adjustable short-circuiting member and the driving member 25. As illustrated in Fig. 2, this means consists of a threaded bushing 35 having diametrically opposed extensions 36 and 37. The threaded portion of the bushing engages lead screw 25 while the extensions 36 and 37 thereof project, respectively, through slots 17 and 18 of the inner conductor to be secured to the short-circuiting member by way of machine screws 38. Also, extension 36 is sufficiently long to extend through longitudinal slot 16 of outer conductor 10 to serve as an indicator for permitting the position of the short-circuiting member to be determined upon inspection. A calibrated scale (not shown) is associated with slot 16 so that extension 36, in conjunction therewith, provides a direct indication of the resonant wave length of the transmission line for each adjustment of its short-circuiting element.

An additional threaded bushing 40, having the same general configuration as bushing 35, is also included in the line arrangement. This additional bushing is slideable along a pair of studs 41 and 42 extending from bushing 35. Each of the bushings is centrally recessed to house a helical spring 43. The added bushing, in conjunction with spring 43, constitutes an anti-backlash mechanism.

Energy may be supplied to or taken from the transmission line by means of pickup devices 53 which may be accommodated by suitable receptacles 50 and 51 projecting through conductor 10 as clearly disclosed in Fig. 3. These receptacles are preferably diametrically opposed and therefore the circuit arrangements coupled thereto are shielded by the centrally located inner conductor 11.

The current-carrying elements of the line structure, such as conductors 10 and 11 and contact fingers 21 and 22 may be formed of brass and are, preferably, silverplated to have improved conductivity characteristics. Shaft 24, however, is preferably machined from steel stock.

The illustrated embodiment of the invention effectively comprises a coaxial transmission line which is short-circuited at each end and may, therefore, be considered as a resonant cavity. The effective electrical length of the cavity is equal to one-half its resonant wave length and may be adjusted by displacing the short-circuiting member along its inner and outer conductors to tune the cavity over a predetermined range of operating wave lengths. In this connection it will be apparent that the wave-length range is determined by the permissible range of displacements of the short-circuiting member. Therefore, the physical lengths of conductors 10 and 11, which are shown indefinitely in Fig. 1, are selected with a view to obtaining a desired range of operating wave lengths.

The schematic circuit diagram of Fig. 4 represents the application of the described line arrangement to a wave meter system for determining the operating wave length of an oscillation generator 53. A coupling loop 52, coupled to generator 53 and extending into the resonant cavity by way of one of its receptacles 50 or 51, excites the cavity. A second coupling loop 54 extending into the resonant cavity through the other of its receptacles couples a detector 55 thereto. The output circuit of the detector is

coupled to a meter 56, such as a voltmeter. In operating the wave meter system, lead screw 25 is rotated by crank 31. The slots of inner conductor 11 lock bushing 35 against rotation so that this bushing and the short-circuiting member carried thereby are displaced along conductors 10 and 11 by lead screw 25. This adjustment of the short-circuiting member varies the electrical length of the resonant cavity, tuning the cavity over its range of operating wave lengths. When the effective electrical length of the cavity corresponds to one-half the operating wave length of the oscillator, a maximum deflection is obtained on meter 56. The operating wave length of oscillator 53 may then be determined from the position of projection 36 with reference to the wave length scale associated with slot 16 in conductor 10.

Figs. 5-8, inclusive, illustrate the application of the present invention to a transmission line including a pair of spaced parallel conductors associated with a bolometer element to be utilized as a component of a power-measuring bridge network. The line arrangement is enclosed within a conductive shield 100 having a circular cross section and conductive end plates 101 and 102. The transmission line includes a first hollow conductor 103 having a longitudinal slot 104 and carrying at one end a conductive bushing 105 for effectively extending the conductor. A second conductor has a similar construction and consists of a hollow conductive member 106 with a longitudinal slot 107 and a conductive bushing 108. These conductors are assembled in spaced parallel relationship, being secured at one end to suitable recesses in end plate 102 of the shield and being supported at their opposite ends by a disc 109 of insulating material and apertured to receive conductive bushings 105 and 108. Disc 109, in turn, is mounted by means of brackets 110 and 111 to a conductive collar 112 slidable along shield member 100. In order that collar 112 may slide along the shield, the shield is slotted as indicated at 113 and 114, the slots having sufficient width to accommodate brackets 110 and 111. A series of tabs 121 are struck out of collar 112, as shown in Fig. 8, and are depressed frictionally to engage shield 100.

A bolometer element 115, consisting of a center-tapped temperature-variable resistor enclosed within a glass envelope, is supported upon disc 109 by means of insulating straps 116. A conductor 124 connects with the center tap of the bolometer and is drawn through an opening of shield 100 to connect the bolometer element into a bridge network. This element is also electrically coupled to conductors 103 and 106 by way of connectors 117 and 118, extending from the opposite ends of the bolometer element to resilient contact fingers 119 and 120. These contact fingers are secured to disc 109 and are suitably shaped to engage bushings 105 and 108 of the transmission-line conductors 103 and 106, respectively. The adjustable mounting of disc 109 is provided to permit adjustment of the coupling of the bolometer element to the line conductors, for a purpose to be made clear hereinafter. A pickup loop 125 is received by apertures in conductive bushings 105 and 108 and serves to couple the transmission line to a circuit arrangement, such as an oscillation generator, for the purpose of making power measurements. This loop projects through an opening 126 of end plate 101 and may be adjusted longitudinally of the line by means of set screws 127 and 128.

The effective electrical length of the transmission line, including conductors 103 and 106, may be adjusted by means of a conductive short-circuiting member or yoke 130 which is supported by and freely movable along the line conductors. As illustrated in Fig. 7, the short-circuiting yoke 130 is essentially a circular disc apertured to accommodate conductors 103 and 106 and having resilient contact fingers 131 and 132 which engage the line conductors and afford a desired connection to the yoke. An indicator 133, secured to the upper section of yoke 130 and projecting through slot 113 of the shield, enables the position of the short-circuiting member to be determined upon inspection. If desired, the shield may be suitably calibrated to indicate the operating wave length for particular settings of member 130.

As in the described Fig. 1 embodiment, the driving member for effecting displacements of the short-circuiting yoke 130 along the line is provided by one or more lead screws rotatably disposed within the line conductors. Preferably, two such lead screws are provided, one being indicated at 140 and disposed within conductor 103 while the other 141 is located within conductor 106. One end of each lead screw has a reduced cross section and projects through end plate 102 of the shield to support driving gears 142 and 143. A third gear 144, meshing with gears 142 and 143 and supported by a stub shaft 145, provides a unicontrol for effecting identical adjustments of lead screws 140 and 141. Stub shaft 145 is also rotatably supported within end plate 102 and carries upon its free end a crank 146 for controlling the driving members 140 and 141.

As illustrated in Fig. 7, yoke 130 is slotted to receive a pair of threaded vanes 150 and 151 which engage lead screws 140 and 141, respectively, for effecting displacements of the yoke member by the lead screws. Vanes 150 and 151 are locked in position by means of threaded pins 152 and 153 which project through aligned apertures in the yoke 130 and each of the vanes.

Fig. 9 represents a schematic circuit diagram of a bolometer-type power-measuring bridge network, utilizing the line arrangement of Figs. 5-8, inclusive, for measuring the power output of an oscillation generator 155. The bridge network is similar to the well-known Wheatstone bridge in that it essentially comprises a network of resistors. Three of the arms of the bridge are provided by a variable resistor 161 for balancing the bridge network in the face of ambient temperature variations, a variable resistor arrangement 162 calibrated with reference to bolometer element 115 to read directly in terms of power and a fixed resistor 163. The remaining arm of the bridge includes the line arrangement of conductors 103 and 106 and their associated bolometer element 115. The line arrangement is coupled into the bridge circuit by means of the conductor 124 extending from the mid-point of the bolometer element 115 and a second conductor 160 coupled to the shield 100. A source 164 of unidirectional potential is coupled to one pair of diagonal terminals of the bridge and an ammeter 165 is connected between the remaining diagonal terminals. The bridge network is positioned adjacent oscillation generator 155 with its pickup loop 125 inductively coupled thereto, as by way of an inductor 156. While radio-frequency energy is applied to the bolometer element 115 from transmission line conductors 103 and 106, only

direct current is applied to the bridge arrangement in view of the connection 124 to the midpoint of the bolometer and conductor 160 to the shield.

In making power measurements, the bridge network is initially balanced by adjustment of resistor 161 but with the bridge decoupled from the oscillation generator. Having established the initial balance, pickup loop 125 is brought into inductive coupling relation with inductor 156 of the oscillation generator. The position of bolometer element 115 along transmission line 103, 106 as well as the position of its short-circuiting yoke 130 are then adjusted to effect an impedance match between the line arrangement and the oscillation generator for maximum power transfer therebetween. By sliding the disc 109 to vary the position of the bolometer element with reference to the line conductors, an approximate or coarse impedance match is readily obtainable. Through crank 146 lead screws 140 and 141 are rotated to displace the short-circuiting yoke 130 as required to perfect the impedance match.

It will be apparent from the adjustments described that the line arrangement is similar to an adjustable transmission line terminated in an impedance element and having a stub line for providing impedance-matching conditions between the terminating impedance and a circuit to which the line is coupled. In other words, that portion of the line arrangement extending from the connections of the bolometer element 115 with conductors 103 and 106 and including pickup loop 125 may be considered as a line arrangement terminated in a resistive load. The remainder of the line arrangement between the connections to the bolometer element and the short-circuiting yoke 130 may be considered as a stub line, adjustable to effect impedance matching between the composite line arrangement and oscillation generator 155. The energy transferred from the oscillation generator to the transmission line through the coupling between pickup loop 125 and inductor 156 causes a resistance variation in the temperature-variable bolometer element 115 which disturbs the balanced condition of the bridge network. Resistor arrangement 162, calibrated for direct power readings, is adjusted to re-establish a balanced condition in the bridge network and provide the desired indication of the power output of oscillation generator 155.

Each of the described embodiments of the invention features a line arrangement in which the space requirements are minimized. This results from the fact that the physical dimensions of the line remain constant irrespective of the tuning adjustments. Also, in each case the driving member for displacing the short-circuiting element is made of steel stock which is particularly desirable from the mechanical standpoint, while the line conductors have a construction desired to attain optimum electrical characteristics. Furthermore, the driving members may be lubricated as required without disturbing the conductive characteristics of the line conductors.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exerting a controllable driving force along said line, and means projecting through said slot into mechanical-coupling engagement with said adjustable member and said driving member for effecting a displacement of said adjustable member along said path by said driving member.
- 5 2. A transmission line of adjustable electrical length comprising, a first conductor, a hollow second conductor having an axially extending slot and a predetermined spaced relation to said first conductor, an adjustable member movable in a predetermined path in the space between said conductors for varying the electrical length of the transmission line including said conductors, a driving member disposed within said second conductor for exerting a controllable driving force along said line, and means projecting through said slot into mechanical-coupling engagement with said adjustable member and said driving member for effecting a displacement of said adjustable member along said path by said driving member.
- 10 3. A transmission line of adjustable electrical length comprising, a first conductor, a second conductor having an axially extending slot and disposed in spaced parallel relationship to said first conductor, an adjustable member movable in a predetermined path in the space between said conductors for varying the electrical length of the transmission line including said conductors, a driving member disposed within said second conductor for exerting a controllable driving force along said line, and means projecting through said slot into mechanical-coupling engagement with said adjustable member and said driving member for effecting a displacement of said adjustable member along said path by said driving member.
- 15 4. A transmission line of adjustable electrical length comprising, a first hollow conductor, a second conductor having an axially extending slot and coaxially disposed within said first conductor, an adjustable member movable in a predetermined path in the space between said conductors for varying the electrical length of the transmission line including said conductors, a driving member disposed within said second conductor for exerting a controllable driving force along said line, and means projecting through said slot into mechanical-coupling engagement with said adjustable member and said driving member for effecting a displacement of said adjustable member along said path by said driving member.
- 20 5. A transmission line of adjustable electrical length comprising, a first conductor, a second conductor having an axially extending slot and a predetermined spaced relation to said first conductor, an adjustable member supported by at least one of said conductors and movable therealong in the space between said conductors for varying the electrical length of the transmission line including said conductors, a driving member disposed within said second conductor for exert-
- 25 6. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 30 7. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 35 8. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 40 9. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 45 10. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 50 11. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 55 12. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 60 13. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 65 14. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exert-
- 70 15. A transmission line of adjustable electrical length comprising, a first conductor, a second conductor having an axially extending slot and a predetermined spaced relation to said first conductor, an adjustable member supported by at least one of said conductors and movable therealong in the space between said conductors for varying the electrical length of the transmission line including said conductors, a driving member disposed within said second conductor for exert-
- 75 16. A transmission line of adjustable electrical length comprising, a first conductor, a second conductor having an axially extending slot and a predetermined spaced relation to said first conductor, an adjustable member supported by at least one of said conductors and movable therealong in the space between said conductors for varying the electrical length of the transmission line including said conductors, a driving member disposed within said second conductor for exert-

ing a controllable driving force along said line, and means projecting through said slot into mechanical-coupling engagement with said adjustable member and said driving member for effecting a displacement of said adjustable member along said one conductor by said driving member.

6. A transmission line of adjustable electrical length comprising, a first conductor, a second conductor having an axially extending slot and a predetermined spaced relation to said first conductor, an adjustable short-circuiting member engaging each of said conductors and movable therealong in the space between said conductors for varying the electrical length of the transmission line including said conductors, a driving member disposed within said second conductor for exerting a controllable driving force along said line, and means projecting through said slot into mechanical-coupling engagement with said adjustable member and said driving member for effecting a displacement of said adjustable member along said conductors by said driving member.

7. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member including a rotatable lead screw disposed within said second conductor for exerting a controllable driving force along said line, and means projecting through said slot into mechanical-coupling engagement with said adjustable member and said driving member for effecting a displacement of said adjustable member along said path by said driving member.

8. A transmission line of adjustable electrical length comprising, a first conductor, a second conductor having an axially extending slot and a predetermined spaced relation to said first conductor, an adjustable member movable in a predetermined path in the space between said conductors for varying the electrical length of the transmission line including said conductors, a driving member disposed within said second conductor for exerting a controllable driving force along said line, and means secured to said adjustable member and projecting through said slot into mechanical-coupling engagement with said driving member for effecting a displacement of said adjustable member along said path by said driving member.

9. A transmission line of adjustable electrical length comprising, a first conductor, a second conductor having an axially extending slot and a predetermined spaced relation to said first conductor, an adjustable member movable in a predetermined path in the space between said conductors for varying the electrical length of the

transmission line including said conductors, a driving member including a rotatable lead screw disposed within said second conductor for exerting a controllable driving force along said line, and a threaded member extending from said adjustable member through said slot and meshing with said lead screw for effecting a displacement of said adjustable member along said path by said driving member.

10. A transmission line of adjustable electrical length comprising, a first hollow axially-slotted conductor, a second axially-slotted conductor coaxially disposed within said first conductor, an adjustable member movable in a predetermined path in the space between said conductors for varying the electrical length of the transmission line including said conductors and having a projection extending through said slots of said first and second conductors to indicate the position of said adjustable member, and a driving member disposed within said second conductor for exerting a controllable driving force along said line and mechanically engaged by said projection for effecting a displacement of said adjustable member along said path.

11. A transmission line of adjustable electrical length comprising, a first axially-slotted conductor, a second axially-slotted conductor disposed in spaced relationship to said first conductor, an adjustable member movable in a predetermined path in the space between said conductors for varying the electrical length of the transmission line including said conductors, a pair of similar driving members disposed within said first and second conductors respectively for individually exerting a controllable driving force along said line, unicontrol means for actuating said driving members, and means projecting through said slots into mechanical-coupling engagement with said adjustable member and said pair of driving members for effecting a displacement of said adjustable member along said path by said pair of driving members.

12. A transmission line of adjustable electrical length comprising, a first axially-slotted conductor, a second axially-slotted conductor disposed in spaced parallel relationship to said first conductor, an adjustable member movable in a predetermined path in the space between said conductors for varying the electrical length of the transmission line including said conductors and having a pair of projections extending through said slots of said first and second conductors respectively, a pair of similar driving members disposed within said first and second conductors respectively for individually exerting a controllable driving force along said line and mechanically engaged by said pair of projections for effecting a displacement of said adjustable member along said path, and unicontrol means for actuating said driving members.

NICHOLAS V. FEDOTOFF.
